UNITED STATES PATENT OFFICE.

ALFRED H. HAAG, OF BALTIMORE, MARYLAND, ASSIGNOR OF TWENTY ONE-HUNDREDTHS TO E. HOWARD FAIRBANKS, OF MERCHANTVILLE, NEW JERSEY, AND FORTY ONE-HUNDREDTHS TO EMMOR ROBERTS, OF MOORESTOWN, NEW JERSEY.

DESIGN FOR A RADIOCABINET.

Application filed October 19, 1925. Serial No. 15,177. Term of patent 3½ years.

To all whom it may concern:

Be it known that I, ALFRED H. HAAG, a citizen of the United States, residing in the city of Baltimore, in the county of Baltimore City and State of Maryland, have invented a new, original, and ornamental Design for Radiocabinet, of which the following is a specification, reference being had

to the accompanying drawing, forming part hereof, and in which the figure is a view in perspective of my novel radiocabinet embodying my invention.

I claim:

The ornamental design for a radiocabinet, as shown.

ALFRED H. HAAG.
